[57] CLAIM

The ornamental design for a repetitive stamped valve guard, as shown and described.

DESCRIPTION

FIG. 1 is a perspective view of my new design, showing the valve guard applied to a tank assembly with bottom discharge valve, with the tank and valve shown in broken lines; FIG. 2 is a perspective view in elevation thereof; FIG. 3 is a top plan view thereof;

FIG. 4 is a front elevational view thereof;

FIG. 5 is a left end elevational view thereof, the right end being a mirror image;

FIG. 6 is a rear elevational view thereof; and,

FIG. 7 is a cross-sectional view thereof, taken along line 7—7 of FIG. 3.

The broken line representation of the tank and valve in FIG. 1 is for the purpose of illustration and forms no part of the claimed design.
